LEONARD B. TERHUNE, OF NEWARK, NEW JERSEY, ASSIGNOR TO DU PONT VISCOLOID COMPANY, OF WILMINGTON, DELAWARE, A CORPORATION OF DELAWARE

BRISTLE MAGAZINE FOR BRUSH-MAKING MACHINES

Application filed February 11, 1929. Serial No. 338,979.

My invention relates particularly to bristle magazines adapted to be used in connection with brush-making machines, and designed for insertion in and use in connection with any of the different types of brush-making machines.

The object of my invention is to provide magazines for bristles or fibres of any desired kind for feeding the same effectively into any type of brush machine. The object of my invention particularly is to obviate losses in maintenance in such machines by providing a bristle magazine which eliminates mussing of the bristles and which, once 15 the bristles are placed in position the latter, will be uniformly fed to the machine without disturbance or displacement of any kind.

My invention is applicable, for example, to a brush-making machine, as set forth in 20 the patent to Gane No. 378,130, granted February 21, 1888, or the patent to Loomis and Terhune upon machine for making brushes, No. 1,448,489, granted March 18, 1923.

Further objects of my invention will appear from the detailed description of the 25 same hereinafter.

While my invention is capable of embodiment in many different forms, for the purpose of illustration I have shown only one 30 form in the accompanying drawings, in which—

Fig. 1 is a diagrammatic plan view of a bristle magazine made in accordance with my invention;

Fig. 2 is a side elevation of the same;

Fig. 3 is an end elevation thereof; and

Fig. 4 is a vertical section of a detail.

In the drawings, I have shown a magazine-carrying frame 1 which is movably supported upon a main frame 2 of a brush-making machine such as is shown in the patent to Gane above referred to. This frame 1 has supported therein a reel 3 on a pivot 4, which carries wound thereon two narrow strips of 45 spring steel 5 and 6 which may, if desired, be made of steel wire instead, between which there is carried tightly compressed a layer 7 of transversely arranged bristles which have been introduced between the two strips 5 and 6 and which are maintained under pres-

sure in helical form on the reel 3. The outer ends of the strips 5 and 6 are carried around and attached to two similar reels, respectively, 8 and 9, splined loosely by means of slots 8a and 9a, to allow lateral movement thereof, upon shafts 10 and 11 in the magazine frame 1. These shafts 10 and 11 have also removable bushings 10a and 11a projecting into the frame 2 at their lower ends and clips 10b and 11b, with an interposed spring 10c 60 at their upper ends to draw the reels 8 and 9 together. These reels 8 and 9 are provided underneath the frame 1 with reels 12 and 13 supported in a bracket 13a, and which are moved by weights 14, 15 attached thereto by 65 cords 14a, 15a passing over pulleys 16, 16a on the frame 2 for feeding the bristles to the machine according to the rate of consumption of the particular machine. By this means it will be understood that the magazine frame 1, with the reels 3, 8 and 9, may be removed at any time after first removing the clips 10b, 10c and replaced by a new reel 70 fully charged when the supply of bristles has been quite, or almost, exhausted from the particular magazine. As shown in Fig. 1, the magazine frame 1 is so positioned by the pivots 4, 10 and 11 resting within corresponding recesses in the frame 2, that it will remain fixedly in place during the operation 75 of the machine, and will feed the bristles into channel 17 provided in the main frame between bristle guides 18 and 19 from which the bristles are fed to a passageway 20 in which a picker knife 21 and picker 21a operate for conveying the bristles into a slot 22 in an inserting nozzle 23 provided with a reciprocating needle 24 arranged to inject an anchor into the nozzle 23 through a slot 26, as well as said bristles from the slot 22, out 80 of an end 27 of said nozzle into a hole in the brush blank which has been provided for the anchoring of the tuft of bristles by the anchor in said hole of the brush blank. The 85 operation of these parts is conducted in the same manner as in the said patent to Gane above referred to.

By this means, owing to the fact that there is no interference whatever with the position of the individual bristles during the 90 95 100

flow of the same from the magazine to the picker, the bristles will always be in the proper position throughout the feeding operation thereof and will not be subjected to the mousing which occasionally or often occurs in previous magazines utilizing combs or other bristle moving mechanism. Consequently, by the utilization of magazines made in accordance with my invention the maintenance of the brush-making machine is much more readily maintained and the disadvantages and losses due to shutting down the brush-making machine are thereby largely eliminated. The importance of this will be readily appreciated considering the high cost of installation of brush-making machines, as well as the high speed of production when they are in operation, inasmuch as the shutting down of such a machine results in the loss of effective return on the investment as well as a marked decrease in production.

While I have described my invention above in detail I wish it to be understood that many changes may be made therein without departing from the spirit of the same.

I claim:

1. A brush fibre magazine comprising a mechanism including a reciprocating picker for feeding the fibres, and means for transferring the fibres from the body of fibres in the magazine to the point of delivery to the picker without disturbance of the relative position of the fibres during the feeding operation, comprising a spiral flexible retaining means for the body of fibres.

2. A brush fibre magazine comprising a mechanism including a reciprocating picker for feeding the fibres, and means for transferring the fibres from the body of fibres in the magazine to the point of delivery to the picker without disturbance of the relative position of the fibres during the feeding operation, comprising a spiral flexible retaining means for the body of fibres in the form of two lateral supporting strips.

3. A brush fibre magazine comprising a mechanism including a reciprocating picker for feeding the fibres, and means for transferring the fibres from the body of fibres in the magazine to the point of delivery to the picker without disturbance of the relative position of the fibres during the feeding operation, comprising a spiral flexible retaining means for the body of fibres in the form of two lateral supporting metal bands.

4. In combination, a bristle feeding channel for use in connection with brush-making machines, and a brush fibre magazine comprising a mechanism for feeding the fibres and means for transferring the fibres from the body of fibres in the magazine to the channel without disturbance of the relative position of the fibres during the feeding operation, comprising a spiral flexible retaining means for the body of fibres.

5. In combination, a bristle feeding channel for use in connection with brush-making machines, and a brush fibre magazine comprising a mechanism for feeding the fibres, and means for transferring the fibres from the body of fibres in the magazine to the channel without disturbance of the relative position of the fibres during the feeding operation, comprising a spiral flexible retaining means for the body of fibres in the form of two lateral supporting strips.

6. In combination, a bristle feeding channel for use in connection with brush-making machines, and a brush fibre magazine comprising a mechanism for feeding the fibres, and means for transferring the fibres from the body of fibres in the magazine to the channel without disturbance of the relative position of the fibres during the feeding operation, comprising a spiral flexible retaining means for the body of fibres in the form of two lateral supporting metal bands.

7. In combination, a bristle feeding channel for use in connection with brush-making machines, and a brush fibre magazine comprising a mechanism for feeding the fibres, and means for transferring the fibres from the body of fibres in the magazine to the channel without disturbance of the relative position of the fibres during the feeding operation, comprising a spiral flexible retaining means for the body of fibres in the form of two lateral supporting metal bands both of which are arranged in the form of a spiral.

8. In combination, a bristle feeding channel for use in connection with brush-making machines, and a brush fibre magazine comprising a mechanism for feeding the fibres, and means for transferring the fibres from the body of fibres in the magazine to the channel without disturbance of the relative position of the fibres during the feeding operation, comprising a spiral flexible retaining means for the body of fibres in the form of two lateral supporting metal bands arranged in the form of a spiral, and rolls for winding up the bands thereon as they deliver the bristles.

In testimony that I claim the foregoing, I have hereunto set my hand this 29th day of January, 1929.

LEONARD B. TERHUNE.
